US00D341354S

United States Patent [19]

Holterman

[11] Patent Number: Des. 341,354

[45] Date of Patent: ** Nov. 16, 1993

[54] **MEMBRANE OPERATOR INTERFACE
PANEL FOR INDUSTRIAL
PROGRAMMABLE CONTROLLER**

[75] Inventor: **Randall R. Holterman, Mequon, Wis.**

[73] Assignee: **Square D Company, Palatine, Ill.**

[**] Term: **14 Years**

[21] Appl. No.: **747,232**

[22] Filed: **Aug. 19, 1991**

[52] U.S. Cl. **D13/164**

[58] Field of Search **D13/123, 164; D14/240;
D10/106; 361/380, 392, 394; 235/145 R;

[57] **CLAIM**

The ornamental design for a membrane operator interface panel for industrial programmable controllers, as shown.

DESCRIPTION

FIG. 1 is a right front perspective view of a membrane operator interface panel for industrial programmable controllers showing my new design;

FIG. 2 is a front plan view thereof;

FIG. 3 is a right side elevational view thereof;

FIG. 4 is a left elevational view thereof;

FIG. 5 is a back elevational view thereof;

FIG. 6 is a top plan view thereof; and,

FIG. 7 is bottom plan view thereof.

FIG. 1

FIG. 2

FIG. 4

FIG. 3

FIG. 5

FIG. 6

FIG. 7
